FORK OR SIMILAR ARTICLE

Donald A. Wallace, Croton-on-Hudson, N. Y.

Application April 3, 1953, Serial No. 24,336

Term of patent 14 years

(Cl. D54—12)

To all whom it may concern:

Be it known that I, Donald A. Wallace, a citizen of the United States, residing at Croton-on-Hudson, in the county of Westchester and State of New York, have invented a new, original, and ornamental Design for a Fork or Similar Article, of which the following is a specification, reference being had to the accompanying drawings, forming part thereof.

In the drawings:

Fig. 1 is a top plan view of a fork or similar article, showing my new design;

Fig. 2 is a side view;

Fig. 3 is a cross-sectional view taken on line 3—3 of Fig. 1;

Fig. 4 is a cross-sectional view taken on line 4—4 of Fig. 1;

Fig. 5 is a cross-sectional view taken on line 5—5 of Fig. 1;

Fig. 6 is a cross-sectional view taken on line 6—6 of Fig. 1;

Fig. 7 is a cross-sectional view taken on line 7—7 of Fig. 1;

Fig. 8 is a cross-sectional view taken on line 8—8 of Fig. 1;

Fig. 9 is a cross-sectional view taken on line 9—9 of Fig. 1;

Fig. 10 is a cross-sectional view taken on line 10—10 of Fig. 1;

Fig. 11 is a cross-sectional view taken on line 11—11 of Fig. 1; and

Fig. 12 is a perspective view of a fork embodying my new design.

I claim:

The ornamental design for a fork or similar article, as shown.
